UNITED STATES PATENT OFFICE.

ARTHUR O. ZINK, OF RAHWAY, NEW JERSEY.

SOAP.

No Drawing.

Application filed July 9, 1919. Serial No 309,684

To all whom it may concern:

Be it known that I, ARTHUR O. ZINK, a citizen of the United States, residing at Rahway, in the county of Union and State of New Jersey, have invented certain new and useful Improvements in Soap, of which the following is a specification.

This invention relates to a soap or cleansing composition which is adapted to be 10 formed into a sheet or strips.

Heretofore sheet soap has been made by applying a saponaceous composition to one or both sides of a paper carrier or base, which is not soluble in either hot or cold 15 water and is a source of annoyance as well as likely to clog up drains.

The present invention aims primarily to provide a soap or cleansing composition which is capable of being formed into a sheet 20 or strip adapted to meet the requirements of the trade and without a paper carrier or base. It also aims to provide a saponaceous or cleansing composition that will enable the user to effectively remove dirt. Further 25 it aims to provide such a composition that will have a non-deleterious and preferably emollient action upon the hands. Still further it aims to provide a cleansing or saponaceous composition soluble in cold or hot 30 water with the requisite lathering capacity, and preferably also a soap that floats.

The invention consists essentially of a composition of soap or other cleansing substance or substances, one or more binders, 35 one or more non-drying agents, which may or may not have supplementary binding properties, and more or less water according to the use contemplated, the composition being adapted to be formed into a sheet or 40 strip.

To a semi-fluid mass of 40 pounds of a coconut oil soap, 60 pounds of acacia, and 30 pounds of glycerin is added twice as much water by weight, and the solution of a 45 syrupy consistency obtained, preferably by heating, is then put in a beater and whipped to a lather or foam in order to entrap air. This mass or mixture is then spread out on a flat surface and dried after being leveled 50 or gauged off to about $\frac{1}{8}$ " in thickness. The mass is dried either slowly in the air or rapidly by heating. It is desirable to then dust the sheet with a powder, such as soap powder, to prevent its adhesion to rollers in 55 the next succeeding step, which consists in cutting the sheet into strips, and running it

through rollers in order to thin it to the desired gauge. The dusting with soap powder also facilitates lathering.

The resulting product is a thin sheet of 60 soap preferably about $1/50$ " thick which is homogeneous, cohesive or tenacious, saponaceous and pliable. By the term "pliable" is meant "flexible" or that physical condition which permits the thin sheet of soap to be 65 repeatedly folded. If whipped as mentioned above it will contain minute bubbles of air which accelerate solubility or disintegration of the composition. If the beating or whipping is done properly the soap may be made 70 to float, its bulk varying with the extent or thoroughness of aeration and the amount of water retained which ordinarily will be around 25%.

There are many and various substances 75 which may be used to make the composition other than the preferred ingredients above mentioned, the given proportions of which may be varied within wide limits, in most instances as much as forty to fifty per cent. 80

The cleansing agent may be a sodium or potassium soap, or a mixture of the two, a cocoanut oil soap being preferred because it is soluble in salt water and because of its quality.

Instead of acacia, which functions as a binder, I may employ the following substances soluble in cold water, to wit: mesquite gum, dextrin, galatones, glue (soluble), gelanthum, albumin. Or I may employ 90 glycerinated gelatine as a binder, but this substance is soluble only in warm water. Or I may employ the following binders which are disintegrable, if not soluble, in both hot and cold water, to wit: starch mixture, glycerinated starch, gum tragacanth, universal gum, althea root, fibrous pulp. The starch mixture mentioned in the last group of alternative binders may be made from 240 pounds of starch or wheat flour, 7 $\frac{1}{2}$ 100 pounds of alum, 3 $\frac{1}{4}$ pounds of rosin, and 30 pounds of acacia, the alum in which acts upon the starch and renders it adhesive.

Glycerin is the preferred drying resistant, but I may employ glucose and various 105 syrups, such as the trade compound known as "Nulomoline," which in addition have more or less binding power.

Borax, sodium silicate or carbonate, abrasive, perfume, and coloring agents may be 110 incorporated as desired.

The composition soap above described

may be made in strips perforated at intervals for ready detachment to provide an individual wash or it may be made in separate small sheets or pads containing enough soap 5 for a single ablution. Any other convenient way of dispensing the soap may be used however.

To increase the surface area and accelerate lathering the strip or individual pads may 10 be perforated or corrugated or otherwise superficially roughened.

Advertising matter may be imprinted upon the sheet and in colors contrasting with the body of the soap to suit the fancy 15 of the purchaser.

And while I prefer to form the soap into sheets or strips for dispensation, it would be possible to shape the composition into a variety of other forms such as a rod, bar or 20 tube. But for all practical purposes the strip form is most suitable.

Acacia and most, if not all, of the alternative binders previously mentioned are colloidal substances and in the claims the term 25 "colloid" is employed to comprehend the same.

What I claim is:

1. A toilet soap comprising a thin sheet of pliable, strongly tenacious, homogeneous, 30 saponaceous composition.

2. A toilet soap comprising a thin sheet of pliable, strongly tenacious, homogeneous, saponaceous composition disintegrable in water.

3. A toilet soap comprising a thin sheet of pliable, strongly tenacious, homogeneous, saponaceous composition soluble in water.

A toilet article comprising a thin sheet

composed entirely of soap combined with a binder dissoluble in water, and a non-drying 40 agent and capable of being folded repeatedly without rupture.

5. A toilet article comprising a thin, flexible, homogeneous strip composed of soap, 45 acacia and a non-drying agent.

6. A toilet article comprising a thin, flexible, homogeneous strip composed of soap, binder and glycerin.

7. A toilet article comprising a thin, flexible, homogeneous strip composed of soap, 50 acacia and glycerin.

8. A toilet article comprising a thin, flexible, homogeneous strip made from a composition of materials substantially in the proportions of soap forty pounds, binder 55 sixty pounds, and a non-drying agent thirty pounds.

9. The process of making a homogeneous sheet soap consisting in; one, mixing the ingredients; two, thinning the mixture to a 60 syrupy consistency with water; three, aerating the mixture, and four, flowing the aerated mixture on a flat surface and gauging it off to a substantially uniform thickness and five, drying the sheet thus formed.

10. A thin flexible strongly tenacious sheet of soap comprising a soap and a colloid the product being impregnated with air.

11. A thin flexible strongly tenacious sheet of soap comprising a soap, a colloid, and a 70 non-drying agent, the product being impregnated with air.

In testimony whereof, I have signed my name to this specification.

ARTHUR O. ZINK.
